NASAL INHALATOR

Sam Schwartzman, Deforest Corners, Brewster, N.Y., and
Gilbert Schwartzman, 20 Wilmot Circle, Scarsdale, N.Y.

Filed Sept. 17, 1962, Ser. No. 71,728

Term of patent 14 years

(Cl. D83—1)

FIG. 1 is a top perspective view of a nasal inhalator showing our new design in a separated position;

FIG. 2 is a bottom perspective view thereof as shown in FIG. 1;

FIG. 3 is a bottom plan view of the cover member with the remaining portions of the article omitted for convenience of illustration;

FIG. 4 is a top plan view thereof;

FIG. 5 is a side elevational view thereof, with the cover member in an open position; the opposite side being identical; and

FIG. 6 is a side elevational view thereof shown in a closed position.

We claim:

The ornamental design for a nasal inhalator, as shown and described.
